Primary Examiner — Karen E Kearney*Assistant Examiner* — Adam C Mager(74) *Attorney, Agent, or Firm* — Haugen Law Firm PLLP(57) **CLAIM**

The ornamental design for a bogie for a warehousing shuttle, as shown and described.

DESCRIPTION

FIG. 1 is an upper front perspective view of the bogie for a warehousing shuttle of the present invention;

FIG. 2 is a lower rear perspective view of the bogie for a warehousing shuttle of the present invention;

FIG. 3 is an upper front perspective view of the bogie for a warehousing shuttle of the present invention mounted to a shuttle;

FIG. 4 is a front elevational view of the bogie for a warehousing shuttle of the present invention;

FIG. 5 is a rear elevational view of the bogie for a warehousing shuttle of the present invention;

FIG. 6 is a right side elevational view of the bogie for a warehousing shuttle of the present invention;

FIG. 7 is a left side elevational view of the bogie for a warehousing shuttle of the present invention;

FIG. 8 is a top plan view of the bogie for a warehousing shuttle of the present invention; and,

FIG. 9 is a bottom plan view of the bogie for a warehousing shuttle of the present invention.

The broken line showing of environmental structure is for illustrative purposes only, and forms no part of the claimed design.

1 Claim, 7 Drawing Sheets(56)
